UNITED STATES PATENT OFFICE.

ISRAEL KRUTT, OF NEW YORK, N. Y., ASSIGNOR TO WILLIAM A. RAPPEPORT, OF NEW YORK, N. Y.

FOUNTAIN-PEN CLIP.

Application filed July 10, 1924. Serial No. 725,123.

To all whom it may concern:

Be it known that I, ISRAEL KRUTT, a citizen of the United States, and resident of New York, in the county of New York and 5 State of New York, have invented certain new and useful Improvements in Fountain-Pen Clips of which the following is a specification.

This invention relates to a clip structure 10 for fountain pens and the like and to means for retaining such clips in operative position.

While this invention may be applied to articles other than fountain pens, it will be described herein as intended for use upon a 15 fountain pen cap, and with this in mind it may be stated that an object of the invention is to provide a clip which is of simple and strong construction and which may be attached to the cap of a fountain pen, or the 20 equivalent, in a manner which adds no appreciable cost to the cap and yet provides for an unusually firm and substantial means of attachment.

A more detailed object is to provide a clip 25 which is formed from sheet metal having portions of itself bent so as to provide tangs adapted to project inwardly through openings provided in the pen cap, said tangs being shaped to provide enlarged heads at 30 their inner ends and to provide a locking member adapted to be inserted within the cap having a slot to receive said tangs and presenting shoulder portions for engaging 35 said heads to thereby hold the clip against detachment.

A further detailed object is to so shape the tangs and their associated parts as to prevent any appreciable lateral movement 40 of the clip when the locking member is in place.

Other objects and aims of the invention, more or less specific than those referred to above, will be in part obvious and in part 45 pointed out in the course of the following description of the elements, combinations, arrangements of parts and applications of principles constituting the invention, and the scope of protection contemplated will be indicated in the appended claims.

In the accompanying drawings which are 50 to be taken as a part of this specification, and in which I have shown merely a preferred form of embodiment of the invention:

Fig. 1 is a side elevational view of a por-

tion of a fountain pen having a cap thereon which is fitted with a clip constructed in accordance with this invention, parts being illustrated in vertical section for the disclosure of details.

Fig. 2 is a top plan view of the structure shown in Fig. 1.

Fig. 3 is a view similar to that seen in Fig. 2 but illustrating the cap as it appears before attachment of the clip thereto.

Fig. 4 is a plan view of the locking member employed.

Fig. 5 is a transverse sectional view taken substantially upon the plane of line V—V of Fig. 1.

Fig. 6 is a view similar to the upper portion of Fig. 1 and illustrating a modified arrangement of interlocking parts.

Fig. 7 is a transverse sectional view, similar to Fig. 5, but being taken upon the 75 plane of line VII—VII of Fig. 6.

Fig. 8 is a top plan view of the clip employed in connection with the structure in Figs. 6 and 7.

Fig. 9 is a plan view of the locking member employed in connection with the structure in Figs. 6, 7, and 8.

Fig. 10 is a view similar to that seen in Fig. 6 illustrating a further modification of the interlocking parts.

Fig. 11 is a transverse sectional view taken upon the plane of XI—XI of Fig. 10.

Fig. 12 is a top plan view of the clip seen in Figs. 10 and 11, and

Fig. 13 is a plan view of the locking member employed in connection with the structure Figs. 10, 11, and 12.

Referring to the drawings for describing in detail the structure therein shown the reference character L indicates an ordinary fountain pen to which is connected in the usual manner the customary cap or guard member G. Following the present day practice in fountain pen construction this cap is shown to have threaded connection 95 with the pen as at 1 and as including an internal tubular part as 2 arranged to provide a shoulder 3 within the cap adapted to rest against the shoulder portion 4 of the pen for limiting the thread movement of the cap and thereby properly guarding the pen point portion 5 of the pen.

The clip H is made from a single piece of sheet metal of appropriate contour providing what may be termed a body portion 6 110

and a spring portion 7, the usual friction ball as 8 being arranged at the free end of the portion 7.

The body portion 6 is shaped to lie flat 5 against the outer surface of the cap and has two or more tangs as 9 stamped out of the material thereof and bent at right angles to extend through a pair of mating apertures 10 provided in the cap. These tangs have 10 head portions 11 at their inner ends shaped to provide outwardly facing shoulders 12 at opposite sides of a relatively narrow neck 13.

The tubular member 2 is provided with a 15 slot 14 extending longitudinally thereof and is adapted when inserted into the cap G to receive the neck portions 13 of the tangs within its slot 14, the width of said slot being just sufficient for this purpose. Inwardly facing shoulder portions as 15 of the tubular member at opposite sides of the slot have tight rubbing engagement with the outwardly facing shoulders 12 of the tangs so that said tubular member thereby constitutes an effective locking element for preventing any outward movement of the tangs 25 after the tubular member has been inserted.

The engagement of the shoulder portion 4 of the pen L against the end surface of the tubular, or locking, member 2 during the ordinary use of the pen will suffice to at all 30 times prevent tendency of the locking member to work outwardly away from its proper locking position.

In order to restrain the clip against any appreciable sidewise movement within the apertures 10 it is intended that the portions of the tangs which lie immediately within the apertures 10 shall be suitably enlarged 35 as indicated by the reference numeral 16, so as to substantially fill said apertures. In the modification Figs. 6 to 9 the general principle of attachment is the same as already described but in this instance the body portion 6 has its tangs as 17 formed at its longitudinal margins and bent through slots 18 which extend longitudinally of the pen cap. The tangs 17 are arranged so as to incline toward each other at their lower 40 ends and thus provide collectively a dovetailed groove between them into which fits a tongue portion 19 provided upon the locking member 2 and being preferably also of dovetail cross section.

The tangs 17 are also slightly inclined longitudinally relative to each other so that the groove, as 20, formed between them tapers to smaller dimensions at the outer end of said groove and the tongue 19 of the locking member is likewise longitudinally tapered, this arrangement being for the double purpose, first of facilitating easy introduction of the tongue into said groove, it being pointed out that the smaller end of the tongue first enters the larger end of the

groove when these parts are being assembled, and second, to insure firm retention of the clip, it being noted in this connection that the relative sizes of the tongue and groove are such that a considerable pressure 70 is required to wedge the tongue fully home within the groove. The value of the engagement of the pen L against the end surface of the locking member for holding the locking member in its normal position at all times will here be particularly noticeable as a means for preventing likelihood of retrogressive movement of the wedge acting parts of the clip and locking means.

In the modification in Figs. 10 to 13 the 80 structure illustrated is more nearly like the structure appearing in Figs. 1 to 4, the only essential difference being that whereas the tangs in the structure Figs. 1 to 4 are shaped to provide laterally projecting shoulders to be engaged by wall surfaces at opposite sides of a slot in the locking member the structure Figs. 10 to 13 shows the tangs to have central apertures 21 and 22 through 85 which threads a tongue as 23 of the locking member. The aperture 21 is shown to be slightly larger than the aperture 22, and the tongue is shown to be slightly tapered and thereby adapted to serve as a wedge when 90 being inserted into the apertures.

It will be understood of course that the wedge action described in connection with the structures Figs. 6 to 13 could be readily applied to the structure Figs. 1 to 5 by tapering the walls of the slot 14 in the locking member and making the tangs 11 to properly cooperate with said tapered walls after the manner disclosed particularly in the structure Figs. 10 to 13.

Pen clips and caps constructed as herein indicated may be cheaply manufactured and assembled, and the clip will thereafter be firmly and substantially attached to the cap. And it is particularly noted that by tapering the interengaging parts of the clip and locking members, so that they wedge together in the manner shown and described, the clip tangs are not only held firmly against movement out of their receiving openings, but are also held against any lateral movement. This is of prime importance since any movement, however slight, between the clip and the pen cap will produce a certain amount of wear which will ultimately result in a very objectionable movement of the clip. Any such slight movement as may possibly occur in the present structure will be immediately corrected by longitudinal movement of the locking member under pressure of the pen body exerted against the end surface "3" of the locking member.

As many changes could be made in this construction without departing from the scope of the invention as defined in the fol-

lowing claims, it is intended that all matter contained in the above description or shown in the accompanying drawings, shall be interpreted as illustrative only and not in a limiting sense.

Having thus described my invention, what I claim as new and desire to secure by Letters Patent is:—

1. In a pen clip structure, the combination with a pen cap or the like, of a clip member having a body portion arranged to lie flat against the outer surface of said cap having an attaching portion projecting therefrom into the interior of the cap through an aperture provided in the wall of the cap, said attaching portion being shaped to provide a tapered groove dove-tailed in cross section, and a locking member within the cap having a tapered tongue also dove-tailed in cross section adapted to wedge into said groove for holding the clip in position.

2. In a pen clip structure, the combination with a pen cap or the like, of a clip member having a body portion arranged to lie flat against the outer surface of said cap having an attaching portion projecting therefrom into the interior of the cap through an aperture provided in the wall of the cap, said attaching portion comprising a pair of flanges projecting from opposite sides of the body portion and bent so as to incline toward each other and to thereby provide a dove-tailed groove between them, and a locking member within the cap having a tongue adapted to enter said groove for holding the clip in position.

3. In a pen clip structure, the combination with a pen cap or the like, of a clip member having the body portion arranged to lie flat against the outer surface of said cap, having an attaching portion projecting therefrom into the interior of the cap through an aperture provided in the wall of the cap, said attaching portion comprising a pair of ears each having an opening therethrough, and a locking member within the cap having a tongue adapted to enter said openings for thereby holding the clip in position.

4. In a pen clip structure, the combination with a pen cap or the like, of a clip member having the body portion arranged to lie flat against the outer surface of said cap, having an attaching portion projecting therefrom into the interior of the cap through an aperture provided in the wall of the cap, said attaching portion comprising a pair of ears each having an opening therethrough, said ears and the openings thereof being arranged so that said openings are aligned longitudinally of the cap, and a locking member within the cap having a tongue adapted to enter said openings for thereby holding the clip in position.

5. In a pen clip structure, the combination with a pen cap or the like, of a clip member having a body portion arranged to lie flat against the outer surface of said cap, having an attaching portion projecting therefrom into the interior of the cap through an aperture provided in the wall of the cap, said attaching portion comprising an ear bent downwardly from the body portion on a line of bend transverse to the length of the cap, and said ear having its opposite edge surface portions shaped to provide outwardly facing shoulders thereon, and a locking member engaging said shoulders to retain the attaching portion against movement outwardly through the opening of the cap.

6. In a pen clip structure, the combination with a pen cap or the like, of a clip member having a body portion arranged to lie flat against the outer surface of said cap, having an attaching portion projecting therefrom into the interior of the cap through an aperture provided in the wall of the cap, said attaching portion comprising an ear bent downwardly from the body portion on a line of bend transverse to the length of the cap, having an opening formed therethrough, and a locking member within the cap having a tongue adapted to enter said opening for thereby holding the clip in position.

In testimony whereof I affix my signature,
ISRAEL KRUTT.
